UNITED STATES PATENT OFFICE.

DANIEL A. BEAM, OF NEWARK, NEW JERSEY.

DESIGN FOR AN ORNAMENTAL CHAIN.

Specification forming part of Design No. **11,295**, dated July 15, 1879; application filed May 14, 1879.
[Term of patent 3½ years.]

To all whom it may concern.

Be it known that I, DANIEL A. BEAM, of the city of Newark, in the county of Essex and State of New Jersey, have invented a new and original Design for Watch and other Ornamental Chains, of which the following is a full, clear, and exact description, reference being had to the accompanying drawings, forming part of this specification.

The nature of the invention is fully illustrated in the accompanying drawings, in which Figures 1 and 2 are longitudinal views, on an enlarged scale, taken at right angles to each other, of a piece of the chain; and Fig. 3 is a transverse section of one of the links.

The chain is formed of alternating curbed or twisted duplex links A A, of oval form in direction of their margins, with openings b

through their sides parallel to their faces, and circular links B B. The curbed or twisted duplex oval links A are flat in their transverse sections, as shown at x x in Fig. 3. Said links A A are severally linked together independently of the links B B, and the latter links are each linked with two of the links A A.

I claim—

The design for an ornamental chain, consisting of the alternating curbed or twisted duplex oval links A and the circular links B, substantially as described, and shown in the accompanying drawings.

DANIEL A. BEAM.
